UNITED STATES PATENT OFFICE.

EUGENE C. GASPARD, OF CLEVELAND, OHIO.

VEHICLE-WHEEL.

1,380,138.

Specification of Letters Patent. Patented May 31, 1921.

Application filed February 4, 1918. Serial No. 215,374.

To all whom it may concern:

Be it known that I, EUGENE C. GASPARD, a citizen of the United States, residing at Cleveland, in the county of Cuyahoga and State of Ohio, have invented a certain new and useful Improvement in Vehicle-Wheels, of which the following is a full, clear, and exact description, reference being had to the accompanying drawings.

10 This invention relates to vehicle wheels and particularly to devices whereby a demountable tire-carrying rim may be applied to and removed from a fixed rim.

15 It is the general object of the invention to provide a device of this character which, while simple of construction and convenient of application and operation, is efficient for the purpose of forcing a demountable rim laterally to and locking it upon its seat on a fixed rim.

20 Other and more limited objects of the invention will appear hereinafter and will be realized in and through the combinations of elements embodied in the claims.

25 In the drawings accompanying and forming a part of this application Figure 1 represents a detail partly in elevation and partly in section of a fixed rim and locking ring embodying my invention; Fig. 2, a trans-

30 verse sectional view through the fixed rim, locking ring and demountable rim, the plan including the operating devices for said ring; Fig. 3 a sectional detail showing the locking ring in its expanded condition; Figs.

35 4 and 5 are respectively transverse sectional views and a view in side elevation showing the driving connection between the demountable rim and the fixed rim; Fig. 6 a detail in plan of the locking ring and the means 40 for expanding and contracting the same and Fig. 7 a sectional side elevation of the demountable rim and fixed rim.

Describing the various parts in detail, 1 denotes the channeled fixed rim of a wheel 45 having the side flanges 2 and 3. The outer flange 2 is bent to provide a circumferential beveled seat 2^a and an inward extension 2^b of said seat. The inner flange 3 is bent to provide an inner beveled seat 3^a. Secured 50 to the fixed rim is a bushing 4 through which there projects a shaft 5 having a pinion 6 thereon meshing with an elongated pinion 7 carried by the fixed rim. A ring 8 is secured to the shaft and serves as a thrust bearing 55 against the inner end of the bushing. In order to lock the pinions in any desired posi-

tion, the inner end of the bushing is notched, as indicated at 4^a, to coöperate with a locking pawl 9 carried by the shaft. This locking pawl is pivoted within a longitudinal slot 5^a in the shaft, the pivot pin 5^b also serving to retain the ring 8 upon the shaft. The pawl is provided with a nose 9^a adapted, through the action of a spring 10 within the slot 5^a, to engage the notches in the inner end of the bushing, thereby to lock the shaft and pinion in position. The lower or inner end of the shaft is squared for the reception of a socket wrench and the pawl is so arranged that, in applying the wrench to the shaft, the pawl will be engaged by the interior of the socket and will be rocked in a direction to disengage the nose thereof from the bushing, thereby permitting the shaft to be rotated. A dust cap 11 may be applied to the bushing and shaft.

The pinion 7 meshes with racks 12^a upon the overlapping ends of a split locking ring 12. This ring is pivotally connected to the fixed rim by means of links 13, eight such links being shown. The ring is provided with a beveled surface 12^b, for a purpose to be explained hereinafter.

Coöoperating with the seats 2^a and 3^a and with the locking ring 12 is a demountable rim 14. This rim is provided at one side with a radially projecting beveled seat-engaging member 14^a which may be in the form of an integral rib or in the form of spaced lugs. This member is provided with a lateral extension 14^b coöoperating with the extension 2^b of the seat 2^a at its opposite side, the rim is beveled, as shown at 14^c, the beveled surfaces of the demountable rim co-operating with the beveled seats 2^a and 3^a respectively.

The locking ring 12 is provided with a rib 15 having a beveled surface 15^a adapted to be engaged by the beveled surface 12^b of the locking ring thereby to force the demountable rim laterally upon its seats 2^a and 3^a and to retain the said rim upon said seats. The rib 15 will be notched, as indicated at 15^b, to provide clearance for the pinion 7 and the hub 6^a of the pinion 6. This hub forms a bearing for the side of the locking ring adjacent thereto as the ring is expanded and contracted.

16 denotes a driving lug which projects from the demountable rim toward the fixed rim and which is adapted to be received within an aperture 17^a of an angle plate 17

which is secured to the fixed rim and which extends circumferentially thereof. The plate 17 constitutes a driving member projecting toward the demountable rim and having 5 an aperture for the reception of the driving lug 16. In practice, this lug will be inserted into the aperture provided therefor in the plate and with the beveled face 16^a thereof presented toward the flange 2^b whereby it will assist the ring 12 in retaining 10 the demountable rim on its seats. The fixed rim construction shown herein is applicable to ordinary wooden spokes or to wire spokes. In Fig. 3, is shown a construction which may be employed in connection 15 with wooden spokes, the fixed rim being provided with short circular flanges 18 struck therefrom and each surrounding a circular opening adapted to receive a spoke 19. Where my construction is employed with wire wheels, the wire spokes 20 will be directly secured to opposite sides of the bottom of the fixed rim.

It will be noted that the fixed rim flange 25 2 is shorter than the inner flange 3. This enables the rib 15 to clear the outer edge of the flange 2 as the demountable rim is slid laterally upon the fixed rim. Providing the seat extension 2^b not only strengthens the 30 flange 2 but also provides a lateral seat for the extension 14^b of the demountable rim seat 14^a. It will be noted that the beveled seat 3^a constitutes an inclined projection from a flat seat 3^b. By this arrangement, 35 the inner side of the demountable rim is given a double seat and the flange 3^a serves to strengthen the inner side of the fixed rim.

With the parts constructed and arranged 40 as illustrated and described, the operation will be easily understood. By removing the dust cap and applying a socket wrench to the end of the shaft 9 will be unlocked from the bushing and the shaft then 45 rotated in the appropriate direction for contracting the locking ring to permit the removal or application of a demountable rim or in the appropriate direction for expanding 50 the ring to lock a demountable rim in place.

The expanding of the ring will, through 55 the engagement of the beveled surfaces 12^b and 15^a, force the fixed rim laterally and radially along the beveled seats 2^a and 3^a. The links 13 secure the ring to and within 60 the fixed rim and permit it to expand and contract through the action of the pinion 7; and the pawl 9 automatically locks the ring in its expanded and contracted positions as soon as the socket wrench is removed from the shaft.

The construction and arrangement of parts enables a demountable rim to be applied to and removed from a fixed rim in a 65 particularly convenient manner, and re-

quires only a single locking device having a single operating means. The locking ring, its coöperating rib, the driving connection, and the operating means for the ring are all inclosed and protected from the action 70 of dirt and weather. While I have shown the part of the demountable rim which co- 75 operates with the beveled surface of the locking ring as a rib or ring extending substantially continuously from the inner face 80 of said rim, it will be evident that a rib comprising a circumferential series of beveled lugs may be employed in lieu thereof; and the term "rib" is employed in the claims to cover either a substantially continuous or a segmental rib.

Having thus described my invention what I claim is:—

1. The combination with a fixed rim having laterally spaced seats, of a demountable rim having laterally spaced seat-engaging portions and a beveled rib intermediate of such portions, an expansible and contractible ring having a beveled surface adapted to coöperate with such beveled rib, and means for expanding and contracting said ring including pivoted links connecting said ring and said fixed rim for spacing the former equidistant about the latter. 90

2. The combination, with a fixed rim having laterally spaced beveled seats one of which has a lateral extension, of a demountable rim having laterally spaced beveled seat-engaging portions one of which has a lateral extension parallel with the first mentioned extension, and a beveled rib carried by said demountable rim intermediate of such portions, an expansible and contractible ring connected to said fixed rim and having a beveled surface adapted to coöperate with such beveled rib, and means carried by said fixed rim for expanding and contracting said ring. 100

3. The combination, with a fixed rim, of a second rim, means for detachably securing said second rim to said fixed rim, a driving lug projecting from the second rim toward the fixed rim and having an inclined seat edge, and a driving member projecting from the fixed rim toward the second rim 110 and having an aperture for the reception of said lug, the inclined edge of the lug engaging the side edge of the driving member and tending to force the rim laterally on the fixed rim. 115

4. The combination, with a fixed rim and a demountable rim, of means for securing the demountable rim to the fixed rim, said means comprising a split ring having overlapping ends provided each with rack teeth, links supporting said ring from said fixed rim, an elongated pinion interposed between such ends and meshing with said teeth, and means for driving said pinion. 125

5. The combination, with a fixed rim and 130

- a demountable rim, of means for securing the demountable rim to the fixed rim, said means comprising an expansible and contractible ring, a bushing projecting radially within and from the fixed rim, a shaft mounted in said bushing, operating connections between said shaft and ring, and means coöperating with the shaft and bushing for locking said shaft to said bushing.
- 5 6. The combination, with a fixed rim and a demountable rim, of means for securing the demountable rim to the fixed rim, said means comprising an expansible and contractible ring, a shaft operatively connected to said ring, a recessed bushing for said shaft carried by said fixed rim and a pawl pivoted to said shaft and adapted to engage the walls of the recesses in said bushing.
- 10 7. The combination, with a fixed rim and a demountable rim, of means for securing the demountable rim to the fixed rim, said means comprising an expansible and contractible ring, a bushing projecting radially within and from the fixed rim and having 15 its inner end notched, a shaft extending through said bushing and operatively connected to said ring, a pawl pivoted to said shaft and adapted to engage the notches of the bushing and a spring tending to force 20 said pawl into said notches.
- 25 8. The combination, with a fixed rim and a demountable rim, of means for securing the demountable rim to the fixed rim, said means including an expansible and contractible ring, a bushing projecting radially within and from said fixed rim, a shaft 30
- extending through said bushing and operatively connected to said ring, the inner end of said shaft being shaped to receive an operating tool and means normally locking 40 said shaft to said bushing and adapted and arranged to be unlocked by the application of the operating tool to the shaft.
- 35 9. The combination, with a fixed rim having a lateral seat, of a demountable rim, 45 means for detachably securing said demountable rim to said fixed rim, a driving member projecting from the fixed rim toward the demountable rim and having an aperture therein, and a driving lug carried 50 by the demountable rim and having an inclined surface adapted to engage one side of the wall of said aperture to operate as a wedge tending to force the demountable rim laterally toward its seat.
- 45 10. The combination, with a channeled fixed rim the outer edge of the outer flange whereof is beveled and is projected toward the inner flange to provide a double seat, one surface of which is parallel to the axis of 60 the fixed rim, and the outer edge of the inner flange whereof is bent inwardly and then upwardly to provide a double seat, said seats being formed integral with said fixed rim, of a demountable rim having at 65 each side thereof a seating portion adapted to conform to each double seat of the fixed rim, and means for locking said demountable rim in place.
- 55 In testimony whereof, I hereunto affix 70 my signature.
- EUGENE C. GASPARD.
